UNITED STATES PATENT OFFICE.

BENJAMIN T. BABBITT, OF NEW YORK, N. Y.

CONDENSING APPARATUS.

SPECIFICATION forming part of Letters Patent No. 248,981, dated November 1, 1881.

Application filed July 1, 1881. (No model.)

To all whom it may concern:

Be it known that I, BENJAMIN T. BABBITT, of the city of New York, in the county and State of New York, have invented certain new 5 and useful Improvements in Condensing Apparatus, of which the following is a specification.

My invention relates to condensers for steam-engines and other purposes, which are adapted to work without an air-pump, the water being 10 discharged from the condensers against the pressure of the atmosphere by Torricellian columns or barometric legs.

The invention consists in the combination of two chambers provided with steam and water 15 inlets and with water-outlets, to which are connected Torricellian columns or barometric legs, valves in said steam-inlets and water-outlets, floats in said chambers, and a weighted tripping lever or beam, to which the several 20 valves are connected, and which is actuated by said floats to adjust the valves simultaneously, to provide for the alternate passage of steam into one chamber and the alternate discharge of water from the other chamber, whereby I 25 provide an apparatus which is entirely automatic in its action, and which is very desirable because of its simplicity.

The accompanying drawing represents a central vertical section of the apparatus embodying my invention.

A designates two chambers, (here shown as cylindric in form, and of any suitable size, according to the quantity of steam to be condensed.) In the chambers A are floats B, having rods B', which project upward through stuffing-boxes a in the top of the chambers, and are adapted to act alternately upon opposite ends of a beam or lever, C, which is fulcrumed or pivoted in an upright post or column, 35 D, and is provided with an upright projection or arm, C', weighted at b. Thus it will be seen that when either end of the beam C is raised to shift the center of gravity to the opposite side of its fulcrum the movement of the beam 40 will be completed by gravity.

E designates a steam-inlet pipe connecting the two chambers A, and E' designates the pipe by which steam to be condensed is delivered from the engine or other machine into 45 the pipe E. The passage of steam to the chambers A is regulated or controlled by valves c,

(here shown as consisting of ordinary plug-valves,) which are opened alternately by rods d, which form a connection between the beam C and the levers e of said valves. The water 55 for condensing is introduced or injected continuously through two injection-nozzles, f, and the water and steam enter the chambers A together through the steam-inlets.

F designates the discharge or outlet pipes 60 leading from the chambers A, and communicating with or forming Torricellian tubes or barometric legs, which are of sufficient length to deliver the water against the force of the atmospheric pressure. In the discharge-pipes 65 F are valves F', which are attached to a common stem, F², and by moving said stem longitudinally the valves are alternately opened and closed. The stem F² is reciprocated by means of a bell-crank lever, G, receiving motion through a rod, G', from the beam or lever C, and it will be understood that when the steam-valve c of either chamber A is closed the water-valve F' of that chamber is open, and vice versa.

In order to provide for the escape from the chambers A of any air which may enter with the steam and water, I employ a novel form of valve, (shown in section as applied to the left-hand chamber.)

H designates a shell in the top of the chamber A, in which are fitted a double puppet-valve, g, and a float, g'. Any air which may enter the chamber of course rises to the top thereof as the water rises therein, and when the water nearly reaches the top of the chamber is forced out through the valve g; but as soon as all the air is discharged and water passes through the valve g the float g' is raised by the water and closes the valve tightly 90 against its upper seat.

In the drawing I have represented the left-hand chamber A as performing the service of a condenser, while the discharge-valve F' of the right-hand chamber is open and the water 95 is being discharged therefrom. Steam and water enter the left-hand chamber, and the water, gradually rising therein, elevates the float B, and, acting upon the beam C, tilts the same, shutting the cock or valve c of the left-hand chamber and opening the other cock or valve c, whereupon the operation is reversed and

the right-hand chamber is filled, while the full left-hand chamber is discharged.

By my invention I provide a simple and desirable condenser which is continuous and automatic in its action, and with which no air-pump is necessary.

What I claim as my invention, and desire to secure by Letters Patent, is—

1. In a condensing apparatus, the combination of two chambers, each having a steam and water inlet, and a water-outlet communicating with a Torricellian column or barometric leg, valves arranged in said inlets and outlets, a weighted tripping beam or lever with which

all said valves are connected, and floats within 15 said chambers for actuating said beam or lever, substantially as and for the purpose specified.

2. The combination of the chambers A A, the inlet pipe and valves E e, the injection-pipes f, the outlet pipes and valves F F', the 20 tripping beam or lever C, connected with all said valves, and the floats and rods B B', for acting upon said beam or lever, substantially as specified.

B. T. BABBITT.
